CLAIM

The ornamental design for a stackable chair, as shown and described.

DESCRIPTION

FIG. 1 is a perspective view of a stackable chair, looking toward the right front corner, showing my new design;

FIG. 2 is a right side elevation view thereof;

FIG. 3 is a front view thereof;

FIG. 4 is a back view thereof;

FIG. 5 is a top view thereof;

FIG. 6 is a bottom view thereof; and,

FIG. 7 is a perspective view of an alternate embodiment of the stackable chair shown in FIG. 1.
